UNITED STATES PATENT OFFICE.

ARTHUR TREVOR DAWSON, GEORGE THOMAS BUCKHAM, AND WILLIAM ROBERTSON PURVIS, OF WESTMINSTER, LONDON, ENGLAND, ASSIGNEES TO VICKERS LIMITED, OF WESTMINSTER, LONDON, ENGLAND.

ORDNANCE BREECH MECHANISM.

Application filed November 13, 1923. Serial No. 674,455.

To all whom it may concern:

Be it known that we, AETHUR TREVOR DAWSON, GEORGE THOMAS BUCKHAM, and WILLIAM ROBERTSON PURVIS, all subjects of the King of Great Britain, residing at Vickers House, Broadway, Westminster, in the county of London, England, have invented certain new and useful Improvements in or Relating to Ordnance Breech Mechanism, of which the following is a specification.

This invention relates to ordnance breech mechanism of the swinging carrier type in which the opening and closing movements of the carrier are effected through mechanism or gearing which is not of a self-locking character. In such breech mechanisms when used with naval guns the carrier may "take charge" as a result of the roll of the ship, that is to say the momentum acquired by the carrier as a result of the roll of the ship may take the breech mechanism out of the control of the operator who is therefore liable to be injured by the swinging mass or by the operating handlever or hand-wheel.

According to the present invention in order to obviate the above-mentioned difficulty without having to employ low speed self-locking gearing, we provide a self-locking device which operates to retain the carrier in any position in which it is placed until the said device is released by the movement of the operating handlever or hand-wheel in either direction. This device acts between the carrier or a part movable therewith and a part on the gun and may comprise pairs of spring controlled rollers or balls which engage with relatively inclined circumferential surfaces on the said parts to retain the carrier as aforesaid.

In order that the said invention may be clearly understood and readily carried into effect the same will now be described more fully with reference to the accompanying drawings, in which:

Figure 1 is a rear elevation of the breech end of a gun having a breech mechanism operated by a handlever, the device according to the invention and the parts associated with it being shown in section.

Figure 2 is a section taken approximately on the line 2—2 of Figure 1, and drawn to a larger scale.

Figure 3 is a plan of the breech end of a

gun having a breech mechanism operated by a handwheel and gearing which is not self-locking, the devices according to the invention and the parts associated with it being shewn in section.

Figure 4 is a view on a larger scale of part of Figure 3, and

Figure 5 is a section taken approximately on the line 5, 5 of Figure 4 and drawn to a larger scale.

A is part of the gun, B is the breech screw, C is the carrier, c is the carrier axis pin and D is the operating handlever (Figures 1 and 2) or handwheel (Figures 3 to 5).

In the construction shewn by Figures 1 and 2 the handlever D has a boss D¹ rotatably disposed co-axially with the carrier axis pin c in a casing A¹ forming part of or rigidly connected to the gun. A second boss or collar C¹ which is integral with the carrier axis pin keyed to the carrier (or which alternatively may form part of the carrier) is situated co-axially with respect to the first-mentioned boss D¹ and has two lugs c¹, c² disposed, with a certain amount of lost-motion, between two pairs of projections d¹, d² and d³, d⁴ on the boss D¹. The surfaces between the said lugs c¹, c² are so shaped as to provide four cam or inclined faces c³, c⁴—with which spring pressed balls or rollers c⁴, c⁴—engage to lock the carrier to the gun. When the handlever is turned in one direction or the other, the corresponding balls or rollers are moved by one pair of the aforesaid projections out of engagement with the inclined faces after which the other projections come against the aforesaid lugs c¹, c² and the carrier is thereby freely moved in the desired direction. This is the position shewn in Figure 2 during the closing movement of the handlever D. When the handlever is not being operated, the balls or rollers are pressed by their springs into engagement with the inclined faces and the carrier is thereby locked against movement in both directions.

In the construction shewn by Figures 3 to 5 a similar arrangement of self-locking device is employed except that the boss or collar C¹ forms part of one of the gear wheels C², C³ operating a nut C⁴ rotatably mounted in a bracket a pivoted at a¹ to the gun and that the casing A¹ is carried by this bracket; the nut C⁴ engages with a

screw-threaded member C^6 pivoted at C^6 to an arm on the carrier C , the pitch of the threads being such that the nut and the member C^6 do not constitute a self-locking mechanism, that is to say a force applied axially to the said member would result in the nut being turned if the aforesaid self-locking device were not provided.

In both the constructions described the aforesaid casing A^1 may include a hardened ring with the inner surface of which the balls or rollers c^4, c^4 —engage.

What we claim and desire to secure by Letters Patent of the United States is:—

- 15 1. In ordnance breech mechanism, the combination of a movable carrier, means which are not of a self-locking character for operating said carrier, an operating member for said means, a self-locking device which operates to retain the carrier in any position in which it is placed and means operated by said member for releasing said device on movement of said member in either direction.
- 20 2. In ordnance breech mechanism, the combination of a swinging carrier, means which are not of a self-locking character for operating said carrier, an operating member for said means, a self-locking device which operates to retain the carrier in any position in which it is placed and means operated by said member for releasing said device on movement of said member in either direction.
- 25 3. In ordnance breech mechanism, the combination of a swinging carrier, means which are not of a self-locking character for operating said carrier, an operating member for said means, a self-locking device acting between a part movable with said carrier and a part on the gun for retaining the carrier in any position in which it is placed and means operated by said member for releasing said device on movement of said member in either direction.
- 30 4. In ordnance breech mechanism, the combination of a swinging carrier, means which are not of a self-locking character for operating said carrier, an operating member for said means, a self-locking device comprising pairs of spring-controlled members which engage with relatively inclined circumferential surfaces on a part movable with said carrier and a part on the gun to retain the carrier in any position in which it is placed, and means operated by said member for releasing said device on movement of said member in either direction.
- 35 5. In ordnance breech mechanism, the combination of a swinging carrier, means which are not of a self-locking character for operating said carrier, an operating member for said means, a self-locking device comprising pairs of spring-controlled members which engage with relatively inclined circumferential surfaces on a part movable with said carrier and a part on the gun to retain the carrier in any position in which it is placed, and means operated by said member for releasing said device on movement of said member in either direction.
- 40 6. In ordnance breech mechanism, the combination of a swinging carrier, a hand-wheel, gearing comprising a screw and nut of quick pitch interposed between said hand-wheel and said carrier for operating the latter, a self-locking device comprising pairs of spring-controlled members which engage with relatively inclined surfaces on a part of said gearing and a part on the gun to retain the carrier in any position in which it is placed, projections on the boss of said handwheel for co-operating with said members, and lugs on said part of the gearing, these lugs being disposed between said projections with a certain amount of lost motion.
- 45 7. In ordnance breech mechanism, the combination of a swinging carrier, a hand-wheel, gearing comprising a screw and nut of quick pitch interposed between said hand-wheel and said carrier for operating the latter, a bracket carrying said gearing, means for pivoting said bracket on the gun, a self-locking device comprising pairs of spring-controlled members which engage with relatively inclined surfaces on a part of said gearing and on said bracket to retain the carrier in any position in which it is placed, projections on the boss of said handwheel for co-operating with said members, and lugs on said part of the gearing, these lugs being disposed between said projections with a certain amount of lost motion.
- 50 8. In ordnance breech mechanism, the combination of a swinging carrier, a hand-wheel, gearing comprising a screw and nut of quick pitch interposed between said hand-wheel and said carrier for operating the latter, a self-locking device comprising pairs of spring-controlled members which engage with relatively inclined circumferential surfaces on a part movable with said carrier and a part on the gun to retain the carrier in any position in which it is placed, and means operated by

said operating member for releasing said spring-controlled members on movement of said operating member.

5. In ordnance breech mechanism, the combination of a swinging carrier, a hand-lever, means which are not of a self-locking character interposed between said handlever and said carrier for operating the latter, a self-locking device comprising pairs of spring-controlled members which engage with relatively inclined circumferential surfaces on a part movable with said carrier and a part on the gun to retain the carrier in any position in which it is placed, projections on the boss of said handlever for co-operating with said members and lugs on said part movable with the carrier, these lugs being disposed between said projections with a certain amount of lost motion.

6. In ordnance breech mechanism, the combination of a swinging carrier, a hand-wheel, gearing comprising a screw and nut of quick pitch interposed between said hand-wheel and said carrier for operating the latter, a self-locking device comprising pairs of spring-controlled members which engage with relatively inclined surfaces on a part of said gearing and a part on the gun to retain the carrier in any position in which it is placed, projections on the boss of said handwheel for co-operating with said members, and lugs on said part of the gearing, these lugs being disposed between said projections with a certain amount of lost motion.

7. In ordnance breech mechanism, the combination of a swinging carrier, a hand-wheel, gearing comprising a screw and nut of quick pitch interposed between said hand-wheel and said carrier for operating the latter, a bracket carrying said gearing, means for pivoting said bracket on the gun, a self-locking device comprising pairs of spring-controlled members which engage with relatively inclined surfaces on a part of said gearing and on said bracket to retain the carrier in any position in which it is placed, projections on the boss of said handwheel for co-operating with said members, and lugs on said part of the gearing, these lugs being disposed between said projections with a certain amount of lost motion.
